ALBERT OSWALD BUECHNER, OF ZÜRICH, SWITZERLAND, ASSIGNOR TO THE FIRM OF
PRANA GESELLSCHAFT FÜR TAGESLICHT-PROJEKTION MIT BESCHRÄNKTER HAF-
TUNG, OF HAMBURG, GERMANY.

METHOD OF MANUFACTURE OF PROJECTION-SCREENS.

1,044,135.

Specification of Letters Patent.

Patented Nov. 12, 1912.

Application filed August 11, 1911. Serial No. 643,608.

To all whom it may concern:

Be it known that I, ALBERT OSWALD BUECHNER, a citizen of Switzerland, and resident of Zürich, Switzerland, have invented certain new and useful Improvements in Methods of Manufacture of Projection-Screens; and I do hereby declare the following to be a full, clear, and exact description of the invention, such as will enable others skilled in the art to which it appertains to make and use the same.

This invention relates to a method of manufacture of refracting or dioptric projection screens with the object in view to provide a practical and economical procedure in the preparation of such screens in order that the desired viewing angle may be attained.

The invention consists in first producing upon a pane of suitable material, a preliminary non-plane surface such as may be readily produced by mechanical means, and second, to alter the reflecting and refracting characteristics of the surface so formed by subsequent treatment to obtain a screen having characteristics not readily attainable by either said means or subsequent treatment alone.

The invention may be practised by first; roughening a pane of transparent material, glass for instance, by the employment of the sand blast or equivalent instrumentalities which produces a very irregular surface with many accidental angles and faults which effect partial and total reflection of light falling upon the plane causing it to appear white and to refract light transmitted through it throughout an angle wider than that desired; and subsequently to treat the pane so roughened by the application of a lacquer or varnish in liquid form which displaces the air in the faults and partially fills the steeper depressions hardening under the influence of surface tension with an outer surface which is made up of myriads of small curved rather than plane surfaces which so alters the reflecting and refracting characteristics of the pane that the white appearance disappears and the angle of vision is narrowed.

In the accompanying drawing the structure so attained is illustrated in section in Figure 1 as it would approximately appear

if greatly magnified, the reference letter A indicating a sand blasted glass plate and B indicating the film of lacquer or varnish applied to its roughened surface.

A modification of the manner in which this invention may be practised involves the first step of sand blasting or otherwise producing the preliminary surface upon the pane as before and then subjecting the surface so roughened to the action of an etching agent such as for instance, hydro-fluoric acid which destroys the faults and total reflecting plane angles and rounds off the edges of the projecting portions thereby producing a surface of myriads of small curved rather than plane surfaces. The structure so attained is illustrated in Fig. 3 as it would approximately appear if greatly magnified, the dotted line C representing the profile of the glass plate A before the acid treatment.

Another modification of the procedure in carrying out this invention again involves the first step of sand blasting a suitable pane A, (see Fig. 2), and then entirely filling out the inequalities of the surface so produced with a transparent material D (Fig. 2) of different refractive index from that of the pane.

Still another modification of this method is to provide by mechanical means, such as by rolling or pressing relatively steep configurations E in the surface of a suitable pane A (see Fig. 4) and then subject the surfaces of these configurations to an etching agent such as hydro-fluoric acid if a glass pane be employed, to produce small irregularities upon the surfaces of these configurations E or produce upon them any of the alterations brought about by the second stages of the process above mentioned.

It is obvious that replicas produced from panes manufactured by this process, though of different material are comprehended within the scope of this invention.

A pane prepared in accordance with this invention may be used with a rear, smooth surface silvered to afford a mirror and when so used is nevertheless a refracting screen depending for its operation upon the passage of the light through the glass to be twice refracted by the prepared surface.

What I claim is:—

The method of manufacturing refract-

105

ing projection screens, consisting in producing a preliminary non-plane surface upon a pane of suitable material and altering the refracting and reflecting characteristics of the surface so provided by subsequent treatment, to lessen reflection and obtain a suitable angle of refraction.

In testimony whereof I affix my signature, in presence of two witnesses.

ALBERT OSWALD BUECHNER.
